DRESS ORNAMENT

Minnie Myers, Kingsville, Tex.

Application November 22, 1950, Serial No. 13,092

Term of patent 14 years

(Cl. D45—19)

To all whom it may concern:

Be it known that I, Minnie Myers, a citizen of the United States of America, residing at Kingsville, county of Kleberg, and State of Texas, have invented a new, original, and ornamental Design for a Dress Ornament, of which the following is a specification, reference being had to the accompanying drawing, forming a part thereof wherein:

Fig. 3 is a view taken from the direction of the bottom of the ornament in Fig. 1 with the attaching means omitted for convenience in illustration.

Fig. 4 is a view taken from the direction of the left of the ornament in Fig. 1 with the attaching means omitted for convenience in illustration, and

The essential features of my design are shown in full lines.

I claim:

The ornamental design for a dress ornament, as shown and described.

MINNIE MYERS.
